US0D1051983S

(12) **United States Design Patent** (10) Patent No.: **US D1,051,983 S**
(45) Date of Patent: ** Nov. 19, 2024

(54) **COPYING MACHINE**

(71) Applicant: **SHARP KABUSHIKI KAISHA**, Sakai (JP)

(72) Inventors: **Osamu Kawata**, Sakai (JP); **Atsushi Kaseno**, Sakai (JP); **Yukio Kanaoka**, Sakai (JP)

(73) Assignee: **SHARP KABUSHIKI KAISHA**, Sakai (JP)

(**) Term: **15 Years**

(21) Appl. No.: **29/811,434**

(22) Filed: **Oct. 14, 2021**

(30) **Foreign Application Priority Data**

Apr. 14, 2021 (JP) 2021-007769D

(51) **LOC (14) Cl.** **14-02**

(57) **CLAIM**

The ornamental design for a copying machine as shown and described.

DESCRIPTION

FIG. 1 is a front, right, top perspective view of a copying machine in accordance with our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof; and,

FIG. 7 is a left side elevation view thereof.

The broken lines in drawings show portions of the copying machine that form no part of the claimed design.

1 Claim, 7 Drawing Sheets
